PRETZEL STICK VENDING MACHINE

Richard E. Drachenberg, Detroit, Mich.

Application February 29, 1936, Serial No. 66,382

3 Claims. (Cl. 312—74)

This invention relates to improvements in the art of vending articles of merchandise but has special reference to pretzel sticks, and provides a specially designed unit that is coordinated with 5 a certain mechanism of the vending machine whereby, upon depositing a coin in the machine, followed by a simple operation thereof, pretzel sticks will be discharged individually from the machine.

10 It is an object of the present invention to provide a vending machine of this class which will be simple in structure, economical of manufacture, durable and highly efficient in use.

Another object of the invention is the provision of a machine so arranged and constructed 15 that a plurality of pretzel sticks may be wound in a pack, each layer of pretzel sticks being separated from the other by a layer of winding material.

20 Another object of the invention is the provision of a core floatingly mounted and about which a plurality of pretzel sticks may be spirally wound with a mechanism cooperating therewith so as to retain the discharge portion of the pack 25 located adjacent the outlet opening.

Other objects will appear hereinafter.

The invention consists in the combination and arrangement of parts hereinafter described and claimed.

30 The invention will be best understood by a reference to the accompanying drawings which form a part of this specification, and in which, Fig. 1 is a front, elevational view of a machine embodying the invention.

35 Fig. 2 is a rear, elevational view with the rear cover removed and parts broken away and parts shown in section.

Fig. 3 is a sectional view taken on line 3—3 of Fig. 5.

40 Fig. 4 is a slightly enlarged longitudinal, central, sectional view of the reel supporting core.

Fig. 5 is a fragmentary, rear, elevational view showing a part of the mechanism with parts broken away and parts shown in section.

45 Fig. 6 is a view similar to Fig. 5 illustrating the working mechanism in a different position.

Fig. 7 is a sectional view taken on line 7—7 of Fig. 3.

Fig. 8 is a rear, elevational view of one of the 50 cam members used in the invention.

Fig. 9 is a side, elevational view of the cam member illustrated in Fig. 8.

Experience has shown that pretzel sticks are quite suitable for being dispensed in vending 55 machines because, due to their size and shape, a

maximum number may be packed in a given space. When laid cross-wise on a paper ribbon and wound so as to form a spiral reel, the pretzel stick may be fed outwardly upon winding the reel on a suitable core and the pretzels may thus be individually dispensed.

The invention comprises a supporting plate 18 having a window 18A formed therein. This plate 18 rests upon suitable supporting legs 18C and is provided on its forward face with a housing 122 10 having an opening in its forward face adjacent one corner closed with a swingable closure 53.

Mounted on the rear face of the plate 18 is a cup-shaped housing or drum 8 projecting outwardly from which are lugs 9 through which 15 bolts 9 may be projected and secured, said bolts 9 projecting from plate 18. The interior of this drum is visible through the window 18A and positioned within the drum are retained the pretzels A which are to be dispensed. These pretzels are elongated sticks and are spirally wound upon a sleeve 1A to which one end of the ribbon or belt 1 is attached. In order to assemble the pretzels in position shown in Fig. 2, the sleeve 1A is removed from its mountings within the drum 20 or housing 8 and the ribbon 1 is stretched out flat. The pretzels are then laid upon this ribbon extending transversely thereof in close relation to each other and when so positioned, the sleeve 1A may then be rolled over the ribbon of pretzels so that the pretzels are wound spirally on the sleeve, each roll of pretzels being separated from the superimposed roll by the ribbon itself. In actual practice, the pretzels would customarily 30 be mounted on the sleeve in this condition when 35 sold by the baker so that the pretzels would be delivered to the place of dispensing ready for insertion into the machine.

When in the machine, the sleeve 1A would be mounted upon the core 2 illustrated in Fig. 4. 40 The sleeve 1A snugly embraces the core 2 and the core 2 may rotate on the shaft 3 but the frictional contact between the sleeve 1A and the core 2 is such as to normally prevent relative rotation of these parts. This core is provided at 45 one end with an inwardly projecting recess 4 in which is fitted a spring 5 engaging at one end the inner end of the recess 4 and at its outer end the inner face of a plate 6 through which the shaft 3 is projected and which is secured on 50 the shaft 3 by means of the cotter pin 7. The shaft 3 is projected through an arm 12 and upset thereover at one end as at 13. The spring 5 serves to maintain the core 2 pressed into engagement with the face of the arm 12 so as to yieldably re- 55

sist rotation of the core 2 on the shaft 3. The lower end of the arm 12, as clearly appears in Figs. 2, 5 and 6, is fixedly mounted on the shaft 14 which projects through the rear wall of the 5 drum or housing 8. Fixedly mounted on the shaft 14 at one end and projecting downwardly therefrom is a rocker arm 11 to the free end of which is attached one end of a spring 16, the opposite end of said spring 16 being attached to an eyelet 17 projecting outwardly from the drum 8. Consequently, the spiral roll of pretzels is swingable mounted within the drum 8 and the spring 16 has a tendency to maintain the arm 12 rocked to the right, as shown in Fig. 2. A 10 spring 19 is stretched around the spiral roll of pretzels and secured at its opposite ends, as at 20 and 21, to the drum 8 so as to maintain the pretzels in compact relation and assist the spring 16 in rocking the arm 12 to the right.

20 A slot 123 is formed in the drum 8 and adjacent this slot is mounted a roller 50 rotating on a shaft 51. The ribbon 1 winds over the roller 50 and thence downwardly rearwardly of the roller 50 so that as the ribbon 1 is unwound around the roller 25 50, the pretzels will be, individually, dropped into the chute 52 where they will be accessible through the opening closed by the swingable closure 53. It has been stated that one end of the ribbon 1 is secured to the sleeve 1A and the ribbon after 30 being led around the roller 50 is then passed around a roller 27 and connected at its free end 25 to a roller 26. The ribbon 1 is wound upon the roller 26 as it is unwound from the sleeve 1A. Consequently, in order to deposit pretzels in the 35 chute 52, it is but necessary to wind the roller 26 in a clockwise direction as viewed from Fig. 5.

The roller 26 is mounted upon the shaft 43, this shaft projecting centrally through the roller 26 and through a pocket 39 formed in one end thereof, as shown in Fig. 3. Positioned in this pocket 40 is a spring 40 engaging at its outer end the plate 41 which is mounted on the shaft 43 and secured thereto by the cotter pin 42. The shaft 43 is 45 rotatably mounted in the bearing 44 which projects inwardly from the inner face of the plate 18. Mounted on the shaft 43 is a pinion 38 which meshes with the pinion 37 rotatably mounted on the shaft 29. This shaft 29 extends through the plate 18. The shaft 29 projects through the roller 50 55 27 which is rotatable thereon and which is secured to the gear 37 so as to rotate in unison therewith by means of the screw 57. Extending inwardly from the plate 18 is a rod 24C on which is rockably mounted a presser plate 24A adapted to engage the ribbon and press the same into firm contact with the roller 27, as clearly appears in Fig. 6 and Fig. 3. This presser plate 24A is normally held in pressing position by means of the coil spring 24B which is positioned on the rod 24C and 60 connected at one end to the hub or bearing 25D which is carried by the plate 18. Mounted on the outer end of the shaft 29 is a handle 28 whereby the shaft 29 may be rotated, the direction of rotation being indicated by the arrow in Fig. 1.

65 The periphery of the roller 27 is provided with suitable dressing to prevent slippage of the ribbon 1 thereover. The mounting of the roller 26 is such that the spring 40 serves to normally retain the roller 26 in engagement with the face of the 70 gear 38, this frictional contact being normally sufficient to effect a rotation of the roller 26 when the gear 38 is rotated, while at the same time permitting slippage when the diameter of the ribbon wound on the roller 26 increases.

75 Fixedly mounted on the shaft 29 is a cam 34

having the shoulders 33, 34B and 34C formed thereon. Projecting outwardly from one face of the cam 34 is the flange 34A and projecting outwardly from the opposite face is a spring arm or dog 35. This arm or dog 35 is adapted to contact the teeth on the gear 37. Mounted at one end on a block 37B is a spring arm 37A which is adapted to ride over the teeth of the gear 37 as it is rotated in one direction and prevent the rotation in the opposite direction, the gear 37 being 10 rotatable in the direction indicated by the arrow in Fig. 5. The cam 34 is fixedly mounted on the shaft 29 by means of the diametrically extending pin 56 extended through the hub of the cam 34 and through the shaft 29, as clearly appears in 15 Fig. 7.

I have illustrated the invention as being coin operated and the coin which may be deposited in the opening 22 of the housing 122 will pass downwardly through the chute 23 to the position of the dotted line B in Fig. 5 so as to rest upon the hub 24, said hub 24 being integral with the plate 18. When the coin is in this position, the machine is ready for operation and the handle 28 may be rocked in the direction of the arrow indicated in 20 Fig. 1 until it strikes a stop. Upon rocking the handle 28 in this direction, the cam 34 will be rocked in the direction of the arrow indicated in Fig. 5. The flanged portion 34A of the cam 34 will engage the coin and force it to the left of the drawing shown in Fig. 5 so as to rock upwardly the dog 30 which is rockably mounted on the shaft 31 and projecting outwardly from which is the link 30' connected to which is one end of a spring 32, the other end being connected to the 30 plate 18. Consequently, the coin in rocking the dog 30 upwardly, will do so against the tension of the spring 32. This dog 30 will be retained in its upwardly rocked position until the shoulder 33 has cleared the end of the dog 30. It is 40 believed obvious that were the coin not present the end of the dog 30 would engage the shoulder 33 and prevent the rotative movement of the cam 34 so that the machine could not be operated without the presence of a coin in the proper location. As the cam 34 is rotated, the roller 27 will be rotated to unwind from the sleeve 1A a predetermined amount of ribbon or belt 1 so that in this predetermined travel of the belt or ribbon, a predetermined number of pretzels A will be 45 deposited in the chute 52.

As shown in Fig. 6, this movement continues until the shoulder 34B is brought into contact with the lug or stop 45 which is mounted on and projecting inwardly from the plate 18. At the 55 same time, the pawl 35 will engage the teeth of the gear 37 and cause it to rotate in the same direction, thus, effecting a rotation of the gear 38 so as to wind upon the roller 26 that portion of the ribbon 1 which has been unwound from 60 the sleeve 1A by the roller 27. When the rotation has reached that point where the shoulder 34B meets the stop or lug 45, the rotative pressure on the handle 28 will be released thereupon. A reverse rotation of the shaft 29 and the cam 65 34 will be effected by the spring 46 which is attached at one end to the stud 47 projecting outwardly from the lug 48, shown in Fig. 5 and Fig. 6, and which is attached at its opposite end by the screw 49 to the cam 34. This spring will 70 effect the reverse rotation until the shoulder 34C engages the lug or stop 45.

A rear cover 54 is detachably mounted on the plate 16 by means of the bolt 55 and a lock 18B. When the spiral roll of pretzels is inserted in 75

position and the free end of the ribbon or belt 1 is connected to the roller 26, the roller 26 may be manually rotated until the belt or ribbon 1 is stretched taut. The rear cover may then be 5 placed in position and the device will be ready for operation as the machine itself will maintain the belt stretched taut at all times during the operation. It is believed obvious that as the pretzels are fed outwardly and the spiral roll is 10 reduced in diameter, the arm 12 will swing to the right to maintain the spiral roll of pretzels always in position for feeding outwardly.

In this way I have provided a structure whereby pretzel sticks may be individually dispensed from 15 a dispensing device while freedom from breakage is obtained and the pretzels may be maintained always in a sanitary condition.

While I have illustrated and described the preferred form of construction I do not wish to limit 20 myself to the precise details of structure shown but desire to avail myself of such variations and modifications as may come within the scope of the appended claims.

Having thus fully described my invention, what 25 I claim as new is:

1. In a vending machine of the class described, a housing; a rockable shaft projecting through one wall of said housing; a supporting arm fixedly mounted at one end on the inner end of said 30 shaft and projecting therefrom radially of said housing; a rocker arm fixedly mounted at one end at the outer end of said shaft; a spring fixed at one end and connected at its opposite end to the other end of said rocker arm for normally 35 tending to rock said shaft in one direction; a core connected to the other end of said supporting arm and rotatable; a winding reel mounted concentrically on said core and rotatable about the axis of said core; a flexible member wound on 40 said core, and being positioned between each layer of said flexible member a layer of separable articles to be dispensed; winding means for winding said flexible member thereon upon the unwinding of said flexible member from said reel, the winding of said flexible member on said winding 45 means effecting a discharge of said separable members.

2. In a vending machine of the class described, a housing; a rockable shaft projecting through 50 one wall of said housing; a supporting arm fixedly mounted on one end of the inner end of said shaft and projecting radially of said housing; a rocker arm fixedly mounted at one end at the outer end of said shaft; a core rotatably mounted on the other end of said supporting arm and positioned 55 within said housing; a winding reel mounted on said core and rotatable about the axis of said

core, said housing having an outlet opening formed therein; a flexible member wound on said core, and being positioned between each layer of said flexible member a layer of separable articles to be dispensed; a roller mounted in said housing and positioned adjacent said outlet opening, said flexible member being positioned around said roller; winding means for winding said flexible member thereon upon the unwinding of said flexible member from said reel, said roller being 10 positioned between said winding means and said reel, the winding of said flexible member on said winding means effecting a discharge of said separable articles through said outlet opening, said roller being positioned between said winding 15 means and said reel; and resilient means cooperating with said rocker arm for normally maintaining said supporting arm rocked to a position for retaining the outermost layer of said flexible member, wound on said layer in contact with 20 said roller.

3. In a vending machine of the class described, a housing; a rockable shaft projecting through one wall of said housing; a supporting arm fixedly mounted on one end of the inner end of said shaft and projecting radially of said housing; a rocker arm fixedly mounted at one end at the outer end of said shaft; a core rotatably mounted on the other end of said supporting arm and positioned within said housing; a winding reel 30 mounted on said core and rotatable about the axis of said core, said housing having an outlet opening formed therein; a flexible member wound on said core, and being positioned between each layer of said flexible member a layer of separable 35 articles to be dispensed; a roller mounted in said housing and positioned adjacent said outlet opening, said flexible member being positioned around said roller; winding means for winding said flexible member thereon upon the unwinding of said 40 flexible member from said reel, said roller being positioned between said winding means and said reel, the winding of said flexible member on said winding means effecting a discharge of said separable articles through said outlet opening, said 45 roller being positioned between said winding means and said reel; and resilient means cooperating with said rocker arm for normally maintaining said supporting arm rocked to a position for retaining the outermost layer of said flexible member, wound on said layer in contact with 50 said roller; a discharge chute projecting downwardly from said outlet opening; and control means for controlling the operation of said winding means.

RICHARD E. DRACHENBERG.
